UNITED STATES PATENT OFFICE.

EDWIN C. GRIFFIN, OF NEWTON, MASSACHUSETTS.

CRUSHING OR PULVERIZING MILL.

SPECIFICATION forming part of Letters Patent No. 769,740, dated September 13, 1904.

Application filed February 13, 1904. Serial No. 193,366. (No model.)

To all whom it may concern:

Be it known that I, EDWIN C. GRIFFIN, a subject of the King of Great Britain, and a resident of Newton, county of Middlesex, State 5 of Massachusetts, have invented an Improvement in Crushing or Pulverizing Mills, of which the following description, in connection with the accompanying drawings, is a specification, like letters and figures on the drawings representing like parts.

This invention relates more particularly to the so-called "centrifugal roller-mill" type of apparatus for crushing or reducing material to required fineness by subjecting such 15 material to the impact of one or more rolls traveling upon an annular die, the roll or rolls having axial rotation as well as bodily rotation with relation to the die.

In another application, Serial No. 166,805, 20 filed by me July 24, 1903, I have shown certain novel features, including the mode of suspending the crushing-roll from the revoluble driving-shaft and means to shield the roll-bearing as much as possible from the entrance 25 of dust and grit.

My present invention has for its object the production of simple and effective means for still more effectually shielding from dust and grit the roll-bearing in a mill of the type substantially as referred to, the construction and 30 arrangement of parts being such that a strong and continuous downdraft is induced around the roll-bearing while the mill is in operation.

The various and novel features of my invention will be fully described in the subjoined specification and particularly pointed out in the following claims.

Figure 1 is a half front elevation and vertical section of a crushing or pulverizing mill embodying one form of my invention, the sectional half being taken on the line 1 1, Fig. 2. Fig. 2 is a partial top or plan view, enlarged, showing a part of the carrier from which the roll-supporting spindle is suspended, with the hood or top of the shield for the roll-bearing. Fig. 3 is a front elevation of the parts of the apparatus illustrated in Fig. 1, the depending portion of the shield being shown in section. Fig. 4 is an inner rear 45 view of the spindle-head, showing the con-

struction thereof, whereby the spindle-head can rock without interference by the hood; and Fig. 5 is a sectional detail taken on the line 5 5, Fig. 2, with the spindle, spindle-head, and cap omitted.

55

Referring to Fig. 1, the bed B, having an upturned curb B² and pan B³, sustains the annular die D, and an imperforate cylindrical casing M² surrounds an upright screen S, erected around the top of the grinding-chamber, an A-shaped frame being erected upon the bed and comprising upwardly-converging standards F, connected by cross-girths F¹ and F².

The vertical roll-driving shaft C is mounted in suitable bearings E¹ E² in the cross-girths and has an attached pulley C³, driven by a belt from a suitable source of power, the standards F being held in true upright position by lateral tension-braces f⁶; but the 60 detailed construction of the parts specified forms no part of my present invention, as they form a portion of the subject-matter of my application, Serial No. 166,805, referred to.

A disk-like carrier C³ is rigidly secured to 65 the lower end of the shaft, the hub c³ of the carrier supporting an upturned guard c⁵, surrounding the lower end of the bearing E², to protect it from the material to be ground introduced to the grinding-chamber through the 70 hopper H, supported on the cross-girth F².

A feed-duct h¹, having a flared or bell mouth h², is bolted to the top of the carrier and surrounds the hub c³, the bell-mouth surrounding the lower end of the hopper H, a portion of the feed-duct being radially extended at h¹⁰, Figs. 2 and 3, to convey the material to the feed-opening c¹⁰ in the carrier.

One or more centrifugally-acting crushing or pulverizing rolls R are suspended from the 85 carrier C³ near its periphery, and each roll is centrally socketed at r³, Fig. 1, to receive the lower end of the roll-spindle T, having an annular enlargement t³ at the upper end of the bearing-hub r of the roll.

95

The roll is rotatably connected with and retained upon the spindle by a coupling t¹, bolted to the roll and shaped to overhang the spindle enlargement t³, the upper end of the coupling being elongated to form a tubular 100

guard t^4 , whose upper end is adjacent the spindle-head N and projecting into a depending circular flange n^{50} thereon.

The spindle-head has a hub n^x , the opposite ends of which are laterally extended between ears c^{30} on the carrier (see Fig. 3) and pivoted on a fulcrum-pin 28, supported in the ears, so that the roll-spindle, rigidly secured to the spindle-head, can swing toward and from the vertical center of the mill, the construction so far described being substantially all as shown in my application referred to, the parts operating as therein set forth.

A hollow cap N^x is screwed upon the threaded upper end of the spindle, the cap serving as an oil-reservoir, the roll-spindle having a longitudinal central duct t^{50} , (see dotted lines, Fig. 1,) opening into the socket r^x , and a short wick-tube r^{51} is inserted in the upper end of the duct, projecting into the cap, so that oil therein can be taken up by a wick in the tube and permitted to drip through the duct to lubricate the roll-bearing, the roll R being rotatably mounted on the spindle.

I will now describe the novel means forming the subject-matter of this application for forcibly directing air down through the carrier C³.

The back of the spindle-head has formed upon it a diagonal curved bearing-surface n^{40} , (see Fig. 4,) which when the cap is screwed down joins a similarly-curved and diagonal surface n^{42} , formed on the back of the cap and at one side thereof, the curvature of the two surfaces then forming a continuous arc struck from the center of the pin 28 as a center. This curved surface co-operates with a portion of the stationary hood to be described forming a part of the shield for the roll-bearing, as will be explained.

The carrier C is apertured at C⁵⁰ (see dotted lines, Fig. 2) to receive each spindle-head, and a tubular shield M¹⁰ is bolted to the carrier in each of said apertures C⁵⁰, the shield surrounding the spindle and coupling between the carrier and the top of the roll, as clearly shown in Figs. 1 and 3. The shield thus depends from the carrier and extends well down below the upper end of the tubular guard t^4 , as shown clearly in Fig. 1, the inner portion of the shield behind the spindle being elevated above the main portion of the carrier, while the outer part of the shield comes up close to the dropped-down and laterally-extended peripheral portion C³⁰ of said carrier.

In order to greatly increase the force and intensity of the downdraft or air-blast through the carrier C³ and shield M¹⁰, (which blast prevents the entrance of dirt or grit to the roll-bearing,) I have mounted on the carrier a hood at the upper or inlet end of each shield, the hood having its open mouth turned in the direction of the rotation of the carrier. The back wall of the hood is formed by a portion of the cylindrical part h' of the feed-duct and

its bell-mouth h², a shoulder 75 (see dotted lines, Figs. 2 and 5) being formed on the exterior of said parts and extending from the upper edge of the bell-mouth downward diagonally to the carrier C³. A boss 76 is formed at the upper end of this shoulder, and the inner edge of the hood-top h⁷⁵ rests on the shoulder and is secured to the boss 76 by a bolt 77. (See Figs. 2 and 5.) The outer edge of the top is bent over at h⁷⁶ and secured to the top of the upright outer wall h⁷⁷ of the hood, as by rivets 78. The top h⁷⁵ extends to the leading side n⁶⁶ of the cap N^x, said side being made vertical adjacent the bearing-surface n⁴², and then the hood-top is cut out to present a rearwardly-extended edge h⁷⁹, which joins the back edge h⁸⁰ of the cut-out portion. Such back edge h⁸⁰ is inclined and also made concave in the direction of its length to fit against the bearing-surfaces n⁴⁰ n⁴², the lower end of said edge h⁸⁰ terminating at the top of the carrier C³. The hood-top h⁷⁵ is then flattened, as at h⁸¹, to rest upon the carrier and is secured thereto by a bolt 81, Fig. 2, and by reference to this figure it will be seen that the flat portion extends forward and has a straight edge h⁸² adjacent the vertical side n⁷⁰ of the spindle-head N.

As shown in Fig. 5, the inner upright end h⁸³ of the outer wall h⁷⁷ of the hood is substantially vertical, and by reference to Fig. 2 it will be seen that the upper part of the spindle-head N and the cap N^x extend into the re-entrant or cut-out portion of the top h⁷⁵ of the hood. The vertical side n⁶⁶ of the cap wipes over the edge h⁷⁹ of the hood-top when the spindle-head rocks on its fulcrum 28, and the concave and diagonal edge h⁸⁰ of the top contacts with the bearing-surfaces n⁴⁰ n⁴², so that the re-entrant portion of the hood-top is maintained closed, while permitting the radial swing of the roll-spindle. Similarly, the edge h⁸² of such re-entrant portion of the hood-top contacts with the vertical side n⁷⁰ of the spindle-head.

The open end or mouth of the hood is bounded by the carrier-top, the leading edges of the wall h⁷⁷ and hood-top h⁷⁵, and by the parts h' h² of the feed-duct, such mouth being open in the direction of rotation of the carrier, (indicated by arrow 100, Fig. 2.) As the carrier is revolved by the shaft C the air rushes into the large open end or mouth of the hood and to the contracted rear end thereof, passing thence down through the shield M¹⁰, the air being forced down through the latter with much power and speed, varying with the speed of rotation of the roll-driving shaft C'. This downdraft or blast effectually prevents the entrance of grit or dirt to the roll-bearing, and consequently reduces wear and tear of the parts.

By reference to Fig. 4 it will be seen that the longitudinal axis of the roll-spindle is not at right angles to the fulcrum-pin 28, the

lower end of the spindle being set ahead somewhat. This is done to cause the roll to have a tendency to rise as it travels upon the die to thereby secure a better grinding action and to prevent any possibility of the roll dragging behind. Inasmuch as the spindle is thus inclined slightly from the vertical, it is necessary to make vertical the sides n^{16} and n^{17} of the cap and spindle-head, respectively, in order that they may move more closely adjacent the coöperating edges of the top of the hood when the roll-spindle swings on its fulcrum 28.

I have described in detail but one hood and the coöperating parts; but it is to be understood that a plurality of crushing-rolls and their spindles may be employed, usually three, arranged equidistant from each other, and each roll-spindle will be provided with a hood, and preferably with a shield, substantially as hereinbefore described.

In some cases the shield may be changed in its particular shape or dimensions without departing from the spirit and scope of my invention, and in treating some kinds of material the shield may be omitted, the gist of the invention residing in forcing a blast or strong draft of air down through the carrier and around the roll-spindle to drive away therefrom dust, grit, or small ground particles of material within the grinding-chamber.

Such details of construction herein shown and described as are common to my pending application above referred to are not claimed herein, as they are fully described and properly claimed in such other application.

My present invention may be varied or modified in different particulars by those skilled in the art without departing from the spirit and scope of my invention.

Having fully described my invention, what I claim as new, and desire to secure by Letters Patent, is—

1. In a mill of the class described, a grinding-chamber containing an annular die, an overhead revoluble carrier, a crushing-roll, a spindle operatively connected therewith, and fulcrumed on the carrier, a tubular shield surrounding the spindle and mounted on the carrier, the lower end of the shield opening into the grinding-chamber and its upper end opening through the carrier, and means mounted on the latter and communicating with the upper end of the shield to collect and force a downblast of air through the shield.

2. In a mill of the class described, a grinding-chamber containing an annular die, an overhead revoluble carrier, a crushing-roll, a spindle operatively connected therewith and fulcrumed on the carrier, a tubular shield surrounding the spindle and mounted on the carrier, the lower end of the shield opening into the grinding-chamber and its upper end opening through the carrier, and a hood mounted on the latter and communicating with the

upper end of the shield, the hood having its open mouth in the direction of rotation of the carrier.

3. In a mill of the class described, a grinding-chamber containing an annular die, an overhead revoluble carrier, a crushing-roll, a spindle operatively connected therewith and fulcrumed on the carrier to swing in a plane radial thereto, the upper end of the spindle projecting above the carrier, a tubular shield surrounding the spindle and depending below the carrier and rigidly attached thereto, the lower end of the shield opening into the grinding-chamber and its upper end opening through the carrier, a hood mounted on the latter and communicating with the upper end of the shield, the mouth of the hood opening in the direction of rotation of the carrier, said hood having its outer wall and top cut out around the upper end of the spindle, and a curved bearing-surface movable with the spindle and concentric with its fulcrum, in contact with the top of the hood at the cut-out portion thereof.

4. In a mill of the class described, a grinding-chamber containing an annular die, an overhead revoluble carrier, a crushing-roll, a spindle operatively connected therewith, a head secured to the upper end of the spindle and fulcrumed on the carrier to permit radial swinging movement of the spindle, a cap connecting the spindle and head and on top of the latter, said cap and head having diagonal, curved bearing-surfaces on their rear sides concentric with the spindle-fulcrum, a tubular, depending shield attached to the carrier and surrounding the spindle, the lower end of the shield opening into the grinding-chamber and its upper end opening through the carrier, and a hood mounted on the carrier and having its mouth open in the direction of rotation of the carrier, said hood communicating with the upper end of the shield, the top of the hood being cut out to receive the spindle-head and coöperating with the bearing-surfaces of the head and cap, to permit swinging movement of the spindle while maintaining the hood-top closed.

5. In a mill of the class described, a grinding-chamber containing an annular die, an overhead revoluble carrier, a crushing-roll, a supporting-spindle therefor depending from and mounted to swing on the carrier, a tubular shield mounted on and depending from the carrier and surrounding the spindle, the lower end of the shield opening into the grinding-chamber, and a hood mounted on the carrier and having a contracted outlet end communicating with the upper end of the shield, the enlarged inlet end or mouth of the hood being turned in the direction of rotation of the carrier, whereby a blast or current of air is collected by the hood and rapidly forced down through the shield into the grinding-chamber.

6. In a mill of the class described, a grinding-chamber containing an annular die, an overhead revoluble carrier having an opening therein, a tubular shield depending from the carrier and opening at its lower end into the grinding-chamber, and at its upper end opening through the aperture in the carrier, a spindle fulcrumed on the carrier, and extended downward through the aperture therein, a crushing-roll rotatably mounted on the lower end of the spindle, a hood on the carrier having its inlet end or mouth open in the direction of rotation of the carrier and with its outlet in communication with the upper end of the shield, the latter surrounding the roll-spindle and permitting swinging movement thereof, the outer side and top of the hood being cut away, and means mounted on the upper end of the spindle to coöperate with such cut-away portions of the hood to close the same while permitting free swinging

movement of the spindle with relation to the carrier.

7. In a mill of the class described, a grinding-chamber containing an annular die, an overhead revoluble carrier having an opening therein, a crushing-roll, a spindle operatively connected therewith and fulcrumed on the carrier, the spindle depending through the opening in the carrier, and a hood mounted on the latter and communicating with the opening, said hood having its open mouth in the direction of rotation of the carrier, to direct a blast or draft of air downward through the opening and around the roll-spindle.

In testimony whereof I have signed my name to this specification in the presence of two subscribing witnesses.

EDWIN C. GRIFFIN.
